DESIGN FOR A CABINET

George R. Hogan, Chicago, Ill.

Application December 29, 1932. Serial No. 46,648

Term of patent 7 years

To all whom it may concern:

Be it known that I, GEORGE R. HOGAN, a citizen of the United States, and residing at Chicago, in the county of Cook and State of Illinois, have invented a new, original, and ornamental Design for Cabinets, of which the following is a specification, reference being had to the accompanying drawing forming a part thereof.

Fig. 1 is a top plan view of a cabinet, showing my new design.

Fig. 2 is a side elevational view thereof, on a reduced scale, the other three sides being identical with the one shown.

I claim:

The ornamental design for a cabinet as shown and described.

In witness whereof, I hereunto subscribe my name this 20th day of December, A. D. 1932.

GEORGE R. HOGAN.
